PERMANENT WAVE APPARATUS

Application filed March 8, 1932. Serial No. 597,549.

My invention relates to permanent wave apparatus and has for an object the provision of apparatus of this character which may be operated without fear of injury to the scalp or the hair by direct contact therewith of highly heated metallic surfaces.

A still further object of my invention is to provide means for greatly simplifying the operation of arranging the hair upon the curling spool and for maintaining operative confinement thereof within a heat chamber of such form and construction that the vapors and gases generated therein will effectively penetrate the hair and then find egress from the chamber as rapidly as said vapors and gases shall have effected their purpose in the curling operation.

Another object of the invention is to provide novel and effective means for enclosing the spool within the heat chamber of the structure and for compelling the vapors and gases to find escape therefrom at such places where they will not be discharged against the head of the person whose hair is being treated.

A still further object of the invention is to provide a simple form of heat chamber which will retain the spool therein in a manner to cause the hair to be exposed to the action of the vapors and gases at a point centrally of the position at which said vapors and gases are generated in the chamber, the form and construction of the chamber and its co-acting spool being such that an annular space is formed between the longitudinal surfaces of the spool and the adjacent walls of the chamber throughout the entire length thereof, into which the said vapors and gases are distributed as they are produced.

Another object of the invention is to provide a novel form of heater which co-acts with surfaces of the heat chamber so that the walls of the chamber may be quickly heated.

Another object of the invention is to provide effective means for forming a seal at the point in the heat chamber at which the hair enters the spool, which said seal is characterized by means to prevent the escape of

the vapors and gases from the chamber and which serves also to hold the hair out of direct contact with metallic surfaces of said chamber.

In the accompanying drawings:

Figure 1 is a plan view of the apparatus;

Figure 2 is a section on an enlarged scale taken approximately on line 2-2 of Figure 1;

Figure 3 is a section taken approximately on line 3-3 of Figure 1;

Figure 4 is a bottom plan view of the head clamp showing the bobbin or spool in dot-and-dash lines;

Figure 5 is a view in front elevation of the head clamp;

Figure 6 is a view in plan of the vapor chamber showing the sections thereof opened;

Figure 7 is a vertical longitudinal section through the apparatus showing a slightly modified form of the invention;

Figure 8 is an end view thereof;

Figure 9 is a section taken on line 9-9 of Figure 7.

In carrying the invention into practice and with particular reference to the embodiment shown in Figures 1 to 6, inclusive, use is made of a heat or vapor chamber 10 consisting of complementary sections 11 and 12, and, as illustrated, the section 11 has one of its side edges hinged to a corresponding side edge of the section 12, as at 13. The other side edge of each of the sections 11 and 12 is formed with an inwardly bent flange 14 which is faced with felt 15 or other suitable well known non-metallic material of a nature that will yield when the respective felt surfaces are clamped against the head, as shown in Figure 2. From the hinge 13 the material of each of the sections 11 and 12 is formed to provide a relatively broad flat flange 16, and on reference to Figure 2 of the drawings, it will be noted that these flanges are adapted to come flatwise against each other and to be held in these positions by a heater 17. The heater may be of any suitable well known construction, adapted to be quickly and conveniently applied to or removed from the chamber sections 11 and

12 but same preferably consists of a pair of co-acting jaws 18 and 19, the latter being in the form of a spring, and provided with a curved free extremity 20, which co-acts with 5 an adjacent flat face of the jaws 17, so as to permit both jaws to be readily slipped over the hinge 13 and to exert sufficient pressure against the flanges 16 to hold the chamber sections 11 and 12 closed. From the construction described, it follows that after the hair has been wound upon the bobbin and the latter placed in the chamber, the heater 17 may be slipped over the flanges 16, as 10 shown in Figure 2, at which time the two chamber sections will be held closed during the curling treatment. When the hair has been curled, the heater may be disconnected from said flanges 16 so that the chamber sections can be opened and the bobbin 26 with- 15 drawn from the curl. The head clamp may be released from the hair in the usual manner. The construction is also such that the effective heat distributing surface 21 of the jaw 17 comes flatwise against the corresponding flat face of the adjacent flange 16, whereby heat may be effectively conducted to the walls of the chamber 10 through the respective flanges 16. The jaw 18 is provided 20 with a receptacle portion 22 which is preferably filled with asbestos 23 and mounted in the asbestos is a resistance coil 24 which may be supplied with current through the conductor cord 25. To this point, it manifestly follows that it is intended that heat may be 25 taken into the chamber 10 by reason of the direct contact of the flanges 16 with the mating jaws 18 and 19 of the aforementioned heater, and the purpose thereof will be made known presently.

30 Removably mounted in the chamber 10 is a spool or bobbin 26 of a length to extend from one end of the chamber to the other, and, as illustrated, each end of the said bobbin is provided with a short hub 27 which is 35 journaled in a corresponding opening 28 in the adjacent bracket arm 29 of the lower jaw 30 of a head clamp 31. The said clamp is provided with a swinging jaw 32 which is preferably constructed of rubber or other 40 suitable well-known elastic material, so as to come in yielding impingement against the thick portion of a strand of hair when the clamp is closely positioned against the scalp of the person whose hair is being treated, whereby the strand of hair after being wound about the bobbin will be yieldingly 45 accommodated between the felt-faced edges of the respective chamber sections 11 and 12. When the jaw 32 is in its closed position, as 50 shown in Figures 2 and 3 of the drawing, a resilient latch 33 carried by the jaw 30 engages over a keeper projection 34 at the free end of the jaw 32 so as to confine the latter in its clamped or closed position.

55 The bobbin or spool 26 is provided adja-

cent its outer extremities with peripheral grooves 35 which are adapted to receive the inwardly extending flanges 36 formed on the respective sections 11 and 12 of the chamber 10. It is in this manner that the chamber is adapted to effectively enclose the intermediate portion of the bobbin therein so as to prevent the moisture and gases when generated in the chamber from escaping from the ends thereof. The chamber is provided 60 with semi-cylindrical walls 37 which are spaced apart from the walls of the bobbin, being preferably concentrically related thereto, and thereby adapted to receive a pad 38 of absorbent material, the same adapted to be saturated with water or with any gas-generating compound or solution so frequently employed in the curling of hair. I suggest the use of the pad because of the convenience with which it may be incorporated in the organization. Its purpose is to throw off vapors and gases when the walls 37 of the chamber are heated, which said vapors and gases are intended to be brought 65 into effective contact with a strand of hair when wound about the bobbin. This will be fully appreciated on reference to Figure 2 of the drawing. The bobbin is formed with an axial bore 39 and with radial perforations 40, the latter opening at their inner ends into the said bore 39 and at their outer ends into the bobbin receiving space in said chamber. Hair is intended to be curled around the bobbin in the customary manner, and when arranged in its intended order 70 same may be firmly clamped against the bobbin by a pivoted retaining device 41 carried by the bobbin.

75 In operation the thick portion of a strand of hair is first firmly placed between the jaws 30 and 32 of the head clamp and the jaws brought tightly together near the scalp of the person whose hair is being treated, the hair is then wound around the bobbin and clamped in position thereon, and then placed within the chamber 10, the strand of hair adjacent the head clamp 31 passing between the felt faces 15 of the inwardly bent portions 14 of the chamber sections. Before placing the bobbin in the chamber, the moisture container 38 is folded into position, as shown 80 in Figure 2. The heater 17 is then applied and current is taken into the resistance coil so as to bring the metallic receptacle 22 thereof up to the desired heat where there will be sufficient radiation of heat therefrom that will heat the respective walls 37. In so doing the moisture pad is correspondingly heated and vapors and gases are given off therefrom so as to come into the effective presence of 85 the hair which is wound around the bobbin. It follows that the only outlet for the vapors is by way of the passages 40 and the communicating axial bore 39 of the bobbin. I find that in this manner the moisture can be 90

timely conducted out of the chamber and that the time usually required for the waving of the hair may be considerably reduced. I lay particular stress upon the manner in which the hair is passed into the chamber, and it will be observed that at no place does the hair come in direct contact with any of the metallic parts of the curling organization.

In the form shown in Figure 7, the bobbin or spool 42 is formed at its respective ends with heads or disks 43 and 44, which each have a peripheral groove 45 to accommodate the end wall flanges of the complementary chamber sections 46 and 47. These chamber sections are of the same form as the sections 11 and 12 hereinabove referred to. The disk 43 is formed with a slot 48 into which the thick portion of a strand of hair is adapted to pass and to be threaded through the split portion 49 of a felt disk 50. The disk 50 is positioned at one side of the disk 43 and same is intended to close the adjacent end of the chamber so as to prevent the escape of the gases and vapors therefrom. In this form of the invention, the bobbin is intended to radiate away from the scalp, whereas in the other form the bobbin is intended to come almost in parallelism with the scalp. After the thick portion of the strand has been passed through the slot 48 and the slot 49, same is, of course, wound around the body of the bobbin, and when in a fully wound position the bobbin is inserted into the chamber, which consists of the two sections 46 and 47. In this example of my invention, the bobbin is provided with an axial bore 51, which is open at 52 at the far end of the bobbin and closed at 53 outwardly of the disk 43. The walls of the bobbin are also formed with passages 54, the inner ends of which open directly into the bore 51, and their outer ends into the bobbin-receiving space of the chamber. A pad 55, similar to the pad referred to in the first embodiment of my invention, is arranged within the sections 46 and 47, as illustrated. In this form, the sections 46 and 47 are intended to be heated to an extent that will cause vapor and gases to be thrown off from the pad 55 and to be taken into the effective presence of the hair which has been wound around the bobbin. The vapor and gases may freely penetrate the hair and enter the axial bore 52 by way of the radial passages 54, and the same may exhaust into the atmosphere as rapidly as their effect has been spent against the hair.

After the hair has been treated to fully curl same, the circuit (not shown) in which the heater 17 is adapted to be placed, is broken, so as to cut off the transmission of further heat to sections 11 and 12 and thereby enable the said sections to cool sufficiently to permit same to be handled without burning the fingers of the operator.

I claim as my invention:

1. A permanent wave apparatus comprising complementary sections mutually co-acting to define a chamber adapted to contain vapor and gases, and a spool contained in the chamber and spaced from the longitudinal walls thereof, the said spool having an axial bore and a plurality of communicating radial passages, the latter co-acting with the former to establish communication between the exterior of the chamber at the ends thereof and the interior of the chamber to allow free escape of the vapor and gases from said chamber. 70

2. A permanent wave apparatus comprising complementary sections mutually co-acting to define a chamber adapted to contain vapor and gases, a spool contained in the chamber and spaced from the longitudinal walls thereof, the said spool having an axial bore and a plurality of communicating radial passages, the latter co-acting with the former to establish communication between the exterior of the chamber at the ends thereof and the interior of the chamber to allow free escape of the vapor and gases from said chamber and a moisture holder in said chamber. 85

3. A permanent wave apparatus comprising complementary sections mutually co-acting to define a chamber adapted to contain vapor and gases, a spool contained in the chamber and spaced from the longitudinal walls thereof, the said spool having an axial bore and a plurality of communicating radial passages, the latter co-acting with the former to establish communication between the exterior of the chamber and the interior thereof, and a moisture holder in said chamber, said holder comprising a pad of absorbent material folded to occupy a concentric position relative to the spool. 90

4. A permanent wave apparatus comprising a chamber, a spool removably supported in the chamber and provided with radial passages and a longitudinal bore, the former opening into the chamber and communicating with the bore and said bore opening at its ends to the exterior of the chamber, and means of non-metallic yielding material for sealing the chamber at the point of entrance of a strand of hair thereinto in passage of the hair onto the spool. 100

5. A permanent wave apparatus comprising a chamber comprising complementary sections hinged together at one side and provided with flanged portions, a spool contained in the chamber, and a heater including co-acting jaws adapted to receive the said flanged portions and to act thereon to hold the chamber sections closed about said spool. 115

6. A permanent wave apparatus comprising a chamber having complementary sections hinged together at one side and pro- 120

- vided with flanged portions, a spool contained in the chamber, and a heater including co-acting jaws adapted to receive the said flanged portions and to act thereon to hold 5 the chamber sections closed about said spool, the said sections having heads at the ends thereof with which the respective ends of the said spool are detachably connected.
7. A permanent wave apparatus comprising a chamber comprising complementary sections hinged together at one side and provided with flanged portions, a spool contained in the chamber, and a heater including co-acting jaws adapted to receive the said 10 flanged portions and to act thereon to hold the chamber sections closed about said spool, the said sections having heads at the ends thereof with which the respective ends of the said spool are detachably connected, and 15 the said spool having an axial bore and radial passages, the latter co-acting with the former to establish communication between the exterior of the chamber and the interior thereof.
8. A permanent wave apparatus comprising a chamber comprising complementary sections hinged together at one side and provided with flanged portions, a spool contained in the chamber, and a heater including co-acting jaws adapted to receive the said 20 flanged portions and to act thereon to hold the chamber sections closed about said spool, the said sections having flanges at the ends thereof with which the respective ends of the said spool are detachably connected, and the 25 said spool having an axial bore and radial passages, the latter co-acting with the former to establish communication between the exterior of the chamber and the interior thereof, and a moisture container separable from 30 the chamber and embracing the spool so that vapor discharging therefrom may pass out of the chamber through the aforementioned communicating bore and passages.
9. A device of the class described comprising a spool around which a strand of hair is adapted to be wound, means forming a heat chamber in which the spool is adapted to be contained, the chamber means having a member adapted to contain a vapor producing 35 fluid, and means for heating said member, and means for conducting vapor and gases from the chamber by way of the spool.
10. A device of the class described comprising a spool around which a strand of hair is adapted to be wound, means forming a heat chamber in which the spool is adapted to be contained, the chamber means having a member adapted to contain a vapor producing fluid, and means for heating said member so 40 as to generate vapor at the member and around the spool, and means co-operable with the chamber means for causing the vapor to find egress therefrom.
11. In a device of the class described, a 45 spool around which a strand of hair is adapt-
- ed to be wound, the spool having an axial bore and a plurality of passages communicating therewith and having portions leading onto an exterior surface of the spool, means forming an enclosure for the spool and comprising co-operable sections and adapted to contain moisture, the said bore opening to the exterior of said enclosure means, and means for heating the moisture container.
12. In a device of the class described, means comprising complementary sections having abutting edge portions, said sections mutually defining a steam chamber, a moisture pack cooperable with the chamber when the latter is heated and the pack moistened so as to cause steam to be directly generated in the chamber, a spool insertable in and removable from the chamber, means for discharging steam from the chamber as rapidly as same is generated therein, and means for sealing the chamber at the points of abutment of said edge portions of the complementary sections thereof.
13. A device of the class described comprising a steam chamber consisting of complementary sections having longitudinally extending edge portions at one side of the chamber, means for yieldingly pressing the sections together to advance one of said edge portions against the other thereof; means for sealing the chamber at said edge portions to prevent the escape of steam from between same; means within the chamber for generating steam therein when the walls of the chamber are heated; and a spool insertable in and removable from said chamber.
14. In a hair treating organization, the combination with a clamp comprising mating sections for gripping engagement with the hair at a point close to the scalp, of a steam chamber positioned at one side of the clamp and formed of heat retaining material; a moisture containing member for directly generating steam in the chamber when heat is supplied to the latter; means for discharging steam from the chamber as rapidly as same is generated therein; and means co-operable with the chamber at one side thereof to prevent a discharge of steam therefrom in a direction towards said clamp.
